[57] CLAIM

The ornamental design for a belt mounted clip board holder, as shown and described.

DESCRIPTION

FIG. 1 is a perspective view of a belt mounted clip board holder showing my new design;
FIG. 2 is a front elevational view thereof;
FIG. 3 is a left side elevational view thereof;
FIG. 4 is a right side elevational view thereof;
FIG. 5 is a top plan view, the bottom being a mirror image thereof; and
FIG. 6 is a rear elevational view thereof.
